METHOD OF PREPARING CONFECTIONERY

Alex W. Paton, South Orange, N. J., assignor to
Brewster-Ideal Chocolate Company, Newark,
N. J., a corporation of New Jersey

Application March 10, 1936, Serial No. 68,130

2 Claims. (Cl. 107—54)

This invention relates to a method and apparatus for preparing confectionery such as nonpareils, chocolate drops, buds, stars, kisses or wafers.

5 More particularly, the invention pertains to a method and apparatus of depositing such confections in spaced relation of a string, thread or other filamentary structure.

10 A still further object of the invention is to automatically and continuously deposit the said confectionery on a string in such a manner that the string becomes an integral part of the confectionery, after which the string may be severed into desired lengths and these lengths sold as a unit.

15 Referring to the drawing, Fig. 1 is a top plane view of an apparatus for carrying out the above described method.

20 Fig. 2 is a side elevation of the machine partly in cross section.

25 Fig. 3 is a vertical cross section of the confectionery showing its attachment to the string or thread.

30 More specifically in the drawing, and by way of illustration, there is shown a continuous metal belt 1 supported around horizontal cylindrical pulleys 2 and 3, mounted on axles 4 and 5 which are carried on floor brackets 6 and 7. The top flight or surface of the continuous belt 1 is also supported intermediate of the pulleys 2 and 3 on a platform 8 that is mounted between vertically extending spaced side frames 9. The belt is further supported on the bottom of a cooling tunnel 10 which will be hereinafter described in detail.

35 The vertical extending side frames 9 project upwardly beyond the top flight of the belt 1 and between the upper extremities of the frames a trough-like hopper 11 is mounted.

40 As shown in Fig. 2, the hopper 11 is provided with a long depending nozzle 12 having a plurality of spaced apart openings 13 therein, which are in registry with openings 14 formed in horizontal rotary valve shaft 15. The ends of the rotary shaft 15 are carried in suitable bearings formed in the ends of the trough 11 while one end of the shaft 15 extends outwardly through stuffing box 16 and terminates in an end drive pulley 17.

45 The cooling tunnel 10 through which the belt 1 passes and on which it is supported during its passage through the tunnel includes an open-ended casing 18 formed of any suitable construction and is supported on pedestals 19. A cooling coil 20 for the circulation of water or refrigerating medium therethrough is secured in the roof of the cooling tunnel.

5 On vertical side frames 21, mounted adjacent to belt pulley 2 and laterally extending from the rear of the side frames, is a bracket or platform 22 on which is carried a plurality of spindles 23. The vertical side frames 21 are also held together at their upper ends by transverse rod 26. Extending oppositely from the side frames 21 and parallel to the belt 1 are arms 24 transversely joined together at their outer ends by rod 25.

5 Spools or cones 27 of thread, string or the like, 10 are mounted on the spindles 23 with the free ends of the thread or string carried over upper tie rod 26 and down under lower rod 25 in such a manner that the string lies in parallel spaced apart relation on the upper surface of belt 1. 15 The rotary valve 14 in the bottom of the hopper is driven by any suitable means such as an electric motor 28 and belt 28' while the belt 1 is driven by electric motor 29 and drive belt 30, engaging drive pulley 31 carried on an extension 20 of pulley shaft 5.

25 In operation, the hopper 11 is loaded with molten chocolate or any other substantially freely flowing confectionery and rotation of the valve 15 will alternately open and close the openings 25 14 so that the material in the hopper is deposited in drops or gobs on the belt 1, the speed of the belt being so regulated that the chocolate drops, wafers or other forms of confectionery are deposited in spaced relation on the belt. 30

35 It will also be observed that the plurality of strings or threads 27 being carried on the belt 1 are fed directly under the valve openings 13 so that the gobs of confectionery 32 are deposited in spaced relation on said strings. As the belt continues its movement, it carries the molten or semi-plastic confectionery 32, together with the string on which it has been deposited, through the cooling tunnel 10 where the confectionery is cooled and solidifies on the strings. Upon emerging from 40 the cooling tunnel and at the end of the belt, the strings carrying the solidified confectionery are cut off into convenient lengths. 35

What I claim is:—

1. The method of producing candy confections 45 in sales units which includes dropping the individual candies in spaced apart relation and while in a semi-plastic state onto a non-edible filamentary member.

2. The method of manufacturing candies which 50 includes dropping spaced apart transverse rows of individual gobs of candy onto a plurality of spaced apart strings moving in a longitudinal plane, cooling said gobs while in motion and thereafter severing the strings into sales unit lengths. 55

ALEX W. PATON.
